UNITED STATES PATENT OFFICE.

CYRUS A. McCAIN, OF BENSONHURST, NEW YORK.

PRINTING-PRESS INKING MECHANISM.

1,225,668.

Specification of Letters Patent.

Patented May 8, 1917.

Application filed January 6, 1916. Serial No. 70,694.

To all whom it may concern:

Be it known that I, CYRUS A. McCAIN, a citizen of the United States, residing at Bensonhurst, in the county of Kings, State 5 of New York, have invented certain new and useful Improvements in Printing-Press Inking Mechanisms, of which the following is a specification.

The present invention relates to inking 10 mechanisms for flat bed cylinder printing presses in which a reciprocating type bed coöperates with an impression cylinder suitably operated by impression mechanism.

The principal objects of the invention are 15 to provide inking mechanism which shall completely and effectively ink the form from one end to the other with an even film of ink upon all reciprocations of the type bed in regular operation, and do so upon all 20 kinds and cuts of forms, to produce a simple, durable and efficient construction, to construct and arrange the parts so that they will be readily accessible for attention, repair and adjustment and so that they may 25 be readily removed and reassembled, to provide efficient means for moving inking rollers out of engaging position when not in service, in order to prevent their deformation, to provide a novel vibrating mechanism 30 by which both the form vibrating rollers and the ink plate vibrating rollers may have their strokes independently adjusted and adjusted from zero to a maximum, to provide coöperating mechanism be- 35 tween the cylinder tripping mechanism and the mechanism for raising parts of the inking mechanism into their out-of-service position, and in the provision of other features, combinations and details, all of which will 40 be more fully understood upon reference to the following detailed description taken in connection with the accompanying drawing. Such description and drawings set forth the preferred form of my invention 45 and the appended claims set forth its scope.

In the drawing, Figure 1 is a side elevation of a flat bed cylinder printing press embodying all the features of the present invention; Fig. 2 is a diagram of a modified 50 arrangement of form inking and form distributing rollers; Fig. 3 is a detail plan view of the pedal footboard shown directly beneath it in Fig. 1; Fig. 4 is a plan view of a sufficient portion of the press shown in 55 Fig. 1 to illustrate both the rollers for distributing and applying ink to the form and

the rollers for distributing and applying ink to the ink plate; Fig. 5 is a fragmentary plan view of the form duct roller showing the means by which it is operated; Fig. 6 60 is a side elevation of the press taken from the side opposite to that illustrated in Fig. 1; Fig. 7 is a fragmentary view illustrating a further portion of the press not shown in Fig. 6; Fig. 8 is a side elevation of a portion of the press illustrating the form distributing rollers raised away from the form inking rollers; Fig. 9 is a detail elevation of a portion of the mechanism shown in Figs. 6 and 8, illustrating the manner of 65 raising the form inking rollers into their non-service position; Fig. 10 is a detail plan of parts illustrated in Fig. 9; Fig. 11 is an elevation of a portion of the mechanism for vibrating certain of the distributing rollers 70 with the frame shown in section, the plane of section and the direction of the view being indicated by the line 11—11 of Fig. 6; Fig. 12 is a sectional view of parts of the mechanism shown in Fig. 11; Fig. 13 75 80 is an elevation of another portion of the vibrating mechanism with the frame shown in section, the plane of section and direction of view being indicated by the line 13—13 of Fig. 6; Fig. 14 is an elevation of one of 85 the journal boxes employed in supporting certain of the ink plate rollers, illustrating the clip by which the journal of the roller may be held raised in non-service position; Fig. 15 is a central vertical section of the 90 same taken on a plane indicated by the line 15—15 of Fig. 14; Fig. 16 is a detail plan 95 view of the mechanism for advancing the fountain roller; Fig. 17 is an elevation of the same; Fig. 18 is a detail plan of a portion of the frame of the press showing the arrangement of a portion of the gearing and other associated parts, an upright portion of the frame being shown in section; Fig. 19 is a plan view of the vibrating 100 mechanism illustrated in Fig. 11; Fig. 20 is a detail elevation of the mechanism for operating the fountain duct roller and for raising it into non-service position; and Fig. 21 is a detail plan view of the same, 105 parts being broken away to show more clearly the integral relation of the various arms to each other. Throughout these views like characters refer to like parts.

Referring to the drawing in detail, 30 110 and 31 designate the main side frames of the press which is similar in frame construction

to that disclosed in my prior United States Patent No. 1,063,273, granted June 3rd, 1913. These side frames are connected by a plurality of transverse members of which 5 the front member 32 and the intermediate member 33 are shown. The frame carries a reciprocating type bed 34 which travels upon suitable guideways and is reciprocated by any suitable mechanism, preferably that 10 illustrated in my aforesaid patent. The side frames 30 and 31 have upward extensions 35 and 36, respectively, which are recessed at their upper ends to receive the two-part journal boxes 37 and 38, which 15 carry the journals of the impression cylinder 39. The bed 34 is provided at one end with an ink plate 40 and ink is supplied to said plate from a fountain 41 located at the front of the press, by means of a fountain 20 duct roller 42 which is reciprocated back and forth to convey ink from the ink fountain roller 43 to the ink plate 40 and to the associated roller 44, which in turn conveys it to the ink plate roller 45. The duct roller 25 42 first contacts with roller 44 and then with both roller 44 and ink plate 40 as the latter passes under it. Thus the ink is applied directly to the ink plate by the duct roller 42 and the ink plate roller 45. From 30 the ink plate ink is taken up, worked, and distributed by means of the rollers 46, 47 and 48, working together as one set, and the rollers 49, 50 and 51, working together as another set. Of these various rollers, those 35 designated 42, 45, 46, 48, 49 and 51 are composition rollers, and those designated 44, 47 and 50 are steel rollers. The rollers 47 and 50 are vibrating rollers and are adapted to be actuated by the vibrating 40 shaft 52. As the bed travels toward the impression cylinder the ink which has been applied and distributed to the surface of the ink plate 40, is in part taken up by the form duct roller 53 and in part by the form inking rollers 54 and 55. Preferably the duct 45 roller 53 takes up ink from the outer end of the ink plate 40, removing it for a distance equal to the circumference of the roller, and the rollers 54 and 55 take up the balance. The ink taken up by the duct 50 roller 53 is not transferred directly to the form but to a train of distributing rollers 56, 57, 58, 59 and 60. These feed a continuous flow of worked-up ink to the rollers 54 and 55 when passing over the form on the print stroke, thus insuring an even color on the form. Of the several distributing rollers, the rollers 57 and 59 are steel rollers and the remainder are composition rollers; 55 the rollers 56, and 60 are vibratory rollers, actuated from the vibrating shaft 61.

It may be pointed out that in the usual inking mechanisms of the prior art, four rollers are used. The first takes up ink 60 from the ink plate through a distance equal

to its circumference and then continues to roll over the rest of the inked plate. The second roller, following, cleans the plate for a distance equal to its circumference, beginning at the point where the first roller left 70 off. The third and fourth rollers, however, are not inked because the travel of the plate is insufficient. As the ink plate travels in the reverse direction, the two first rollers deposit a good portion of their ink back on 75 the clean table instead of holding it for the form. In contrast to this, in my device the outer roller 53 skips the ink on a portion of the plate and then descends to receive the ink from the outer end of the plate for a 80 distance equal to the circumference of the roller, thereby leaving the balance of the ink, namely, that on the balance of the plate, to be taken up by the rollers 54 and 55. In this way all the ink is taken up from the 85 ink plate and that which the roller 53 takes up goes through the form distributing rollers and is fed continuously to the rollers 54 and 55. The latter, therefore, deposit upon the form not only the ink which they 90 themselves have taken up but also that which is fed to them through the distributing rollers. As a result of this construction a larger ink plate may be employed and an even color across the sheet is insured.

It requires a greater travel of bed and cylinder when four rollers are used, in order to have the last roller clear the form when the type bed is on the front center. With my device the last roller is the form duct 100 roller and it does not roll on the form; therefore I am able to reduce the size of the cylinder and driving gears for a given size of sheet, thereby reducing the travel of the bed and cylinder, and therefore increasing 105 the number of sheets printed when maintaining the same surface speed of bed and cylinder. From tests made, my device gives a much better distribution than with four rollers.

Referring to the fountain roller 43 and its actuating mechanism, I have provided the same with a ratchet wheel 62 which is keyed to the shaft of the roller, as clearly shown in Figs. 16 and 17. A dog 63 engages the teeth 110 on the ratchet wheel to advance the roller 43 through a definite angular distance upon each advance of the dog. As the dog recedes, it slips over the teeth without actuating the wheel 62. A spring 64 engages the 115 dog and causes it to engage the ratchet teeth upon its advance movement. The dog 63 is pivoted upon a pin 65 which extends laterally from a projection 66 upon a loose sleeve 67 mounted upon the roller shaft and permanently secured to a gear wheel 68 by a key 69. As the gear wheel is rotated back and forth the dog 63 advances the roller 43 through definite angular distances in response to the reciprocations of a rack 70 120 and pinion 71. The gear wheel 68 is secured to the roller shaft by a key 72. The roller 43 is 125 mounted upon a shaft 73 which extends laterally from a projection 74 upon a loose sleeve 75 mounted upon the roller shaft and permanently secured to a gear wheel 76 by a key 77. As the gear wheel is rotated back and forth the roller 43 advances the roller 43 through definite angular distances in response to the reciprocations of a rack and pinion 78 and 79.

which engages the teeth on the gear wheel to oscillate it. To secure a nice adjustment of these advance movements of the fountain roller 43, I provide a wheel 70^a which is mounted loosely upon the fountain roller spindle. This wheel has a flange 70^b provided with a series of spaced notches 70^c cut in its peripheral edge. A flat spring 70^d is secured to the fountain frame 70^e by a screw 70^f and extends upward, terminating at its upper end in an angular bend 70^g which may be seated in any one of the notches 70^c to set the wheel 70^a in any desired position. The wheel 70^a also has a flange 70^h which has a peripheral cam face upon which a pin 70ⁱ extending laterally from pawl 63 is adapted to ride. The position of the point 70ⁱ at which the pin 70ⁱ passes from the elevated to the depressed portion of the cam face, determines the point in the stroke of the dog 63 at which it will engage a tooth of the ratchet wheel 62. And the extent of the movement of the pawl 63 after a tooth is thus engaged, determines the extent of rotation of the fountain roller 43. Obviously the wheel 70^a may be set so that the pawl 63 will not pass the point 70ⁱ and thus no engagement of a tooth be had and consequently no advance of the roller 43. Or it may be set so as to engage a tooth at the beginning of its forward stroke and thus produce a maximum advance of the fountain roller 43. Or, again, it may be set at any intermediate point with a resulting corresponding advance of the fountain roller. The rack 70 is mounted to reciprocate in the guide frame 71 carried upon a suitable stud 72 or other projection from the frame of the press. The rack 70 is connected to a second rack 73 by a rod 74. The rack 73 is engaged by the teeth of a segment 75 pivoted at 76 to a portion of the frame 31. The segment 75 is oscillated by means of a connecting rod or pitman 77 which is connected to a pin 78 on the side of the gear wheel 79 which thereby acts as a crank disk. The pitman 77 is connected to the segment 75 by means of a pin 79^a which is adjustably secured in a slot 79^b in the segment 75. By shifting the pin 79^a toward and from the pivotal point 76, the throw of the rack 70 may be correspondingly shortened and lengthened, as is obvious. The gear wheel 79 is mounted upon a shaft 80 which extends transversely of the press and is journaled in suitable bearings in the side frames 30 and 31. Power is transmitted from the main driving shaft 81 to the gear wheel 79 by a gear train including driving pinion 82 meshing with gear wheel 83 upon a shaft 84, and pinion 85 upon said latter shaft meshing with gear wheel 79. This gearing is so proportioned that the gear wheel 79 makes one revolution for each impression, or, in other words, one revolution for each to-and-fro movement of the type bed. As the wheel 79

rotates, the segment 75 is oscillated and the racks 70 and 73 reciprocated with corresponding forward and backward rotations of the gear wheel 68 and consequent step-by-step advances of the fountain roller 43.

Referring to the fountain duct roller 42 and its actuating mechanism, it will be seen that said roller is journaled in the outer ends of arms 86 and 87, which are respectively pivoted to the side frames 30 and 31 or suitable extensions of said frames. The connection of the arm 87 to the side frame is clearly illustrated in Fig. 21. As there shown, the arm 87 is made integral with arms 88, 89 and 90, and are formed on a common hub 91 keyed to a shaft or spindle 92 which constitutes the pivotal connection of these arms to the side frame 31. The connection of the arm 86 to the side frame 30 is a simple pivotal connection. The outer end of 85 the arm 89 is pivotally connected to the upper end of a vertical rod 93 which passes through guiding openings in flanges 94 and 95 of the transverse frame member 32. This rod carries a collar 96 which is secured to it 90 by a set screw 97. This collar forms the upper abutment of a coiled spring 98 which is coiled about the rod 93 and bears at its lower end against the upper face of the flange 95. The collar 96 may be shifted to 95 vary the compression of the spring to increase or decrease its upward action upon the rod 93. This action tends to normally hold the fountain duct roller 42 against the fountain roller 43. In order to move the 100 roller 42 out of such engagement and in opposition to the action of the spring 98, the spindle 92 is provided with a depending arm 99 which is loosely mounted on the spindle and which is in position to engage a portion of the arm 88. The arm 99 is moved to and fro by a rod 100. As the rod moves in one direction, the shoulder 101 on the arm 99 engages the end of the screw 102 extending through the outer end of the arm 88 and 110 forces the arm 88 and its connected arm 87 in a direction to raise the fountain duct roller 42 out of engagement with the fountain roller and to bring it into position to engage the ink plate 40 and the roller 44. 115 By turning the screw 102 which is threaded through the arm 88 and holding it in place by the locknut 103, a nice adjustment may be obtained between the parts. As the rod 100 moves in the opposite direction, the spring 120 98 acts through the rod 93 and the arm 89 to bring the roller 42 into engagement with the fountain roller 43. This return movement is limited by the engagement of a screw 104, similar to screw 102 and having a locknut 103^a, which passes through a threaded opening in the arm 88 in position to engage the frame as indicated by the dotted line 105 of Fig. 20. The rod 100 is reciprocated by a bell crank lever 106 to one arm of which 130

it is secured. The bell crank lever 106 is pivoted at 107 and the other arm is provided with a cam roller 108 which rides upon a cam 109 mounted upon the shaft 80. This cam is of the proper shape to give the parts the desired reciprocating movements.

Referring to the ink plate rollers it will be seen that the journals of each are mounted in suitable bearings carried at the one end upon a frame 111 and at the other upon a frame 112, the latter of which is vertically movable with reference to the main frame of the machine. One of these bearings, designated 110, is illustrated in detail in Figs. 14 and 15. As there shown, the bearing has a slot-like depression 113 formed between the upward extending portions 114 and 115. The bottom of the depression 113 forms a bearing for the journal of the roller. To properly lubricate the bearing surface, an oil groove 116 is provided. An oil duct 117 connects the oil groove 116 with an oil well 118 formed in the body of the upward extension 114. For the purpose of raising the rollers out of their normal operative engaging position, the bearing 110 is provided with an arcuate clip 119 which is pivoted upon a screw 120, which is threaded at 121 into the body of the bearing. This screw is surrounded by a coiled spring 122 which is turned at one end into an opening in the body of the bearing and at the other end into an opening in the hub 123 of the clip 119. The spring 122 normally yieldingly holds the clip 119 in engagement with the stop pin 124 upon the upward extension 115. A projection 125 on the clip 119 serves as a finger-hold by which the clip may be readily moved by hand out of its position against the stop 40 124 for the purpose of raising the journal of the roller out of its normal bearing, or of lowering it into such bearing. The upper portion of the clip is cut away as shown at 126, to form a seat or bearing for the journal of the roller when in its non-service position. The under face of the hooked portion of the clip fits over the top of the roller journal to hold the roller from jumping up when it is reversing or rolling over the ink plate. The 50 lower portion of the bearing 110 terminates in a pin 127 which rests in a socket 128 and is held in adjusted position by a set screw 129. A suitable opening 130 in the socket 128 enables the bearing to be secured in position upon its supporting frame. This socket member 128 is of course made of different shapes and dimensions to suit the character and location of the roller with which it is to be used. The member 128 shown in Figs. 14 and 15, is that which is employed to support rollers like those designated 47 and 50. Where rollers which are nearer to the ink plate are to be supported, the socket members are shaped as shown at 60 132 and 133.

In the arrangement of plate inking rollers shown, the steel rollers 47 and 50 are positively driven through gearing. For this purpose the spindle of the roller 47 is provided with a gear wheel 134 and the spindle 70 of the roller 50 is provided with a similar gear wheel 135. Since these gear wheels are on rider vibrator rollers, they are made somewhat wider than the gear wheels 136 and 137 with which they respectively mesh. 75 These latter gear wheels mesh with gear wheels 138 and 139, respectively, and gear wheels 138 and 139 mesh with a gear wheel 140 which in turn meshes with a gear wheel 141 mounted upon the same spindle as the 80 sprocket wheel 142. The gear wheels 136, 137, 138 and 139, are mounted on spindles which are secured to the frame 111. The gear wheels 140 and 141 are mounted on spindles which are secured to the main side 85 frame 30. The sprocket wheel 142 co-operates with a second sprocket wheel 143 located on the opposite side of the impression cylinder 39 from it and serving as an idler wheel for the sprocket chain 144 which 90 passes over both of said sprocket wheels and is secured to a plate 145 which is fixed to the bed 34 by bolts or other suitable means 146. As the bed 34 reciprocates, the plate 145 causes the sprocket chain 144 to 95 rotate the sprocket wheels 142 and 143 back and forth in correspondence with the to-and-fro movements of the bed. The rotation of the sprocket wheel 142 upon the same spindle as gear wheel 141 causes the latter 100 and its associated gearing to correspondingly move the rider rollers 47 and 50 back and forth.

Referring to the form inking rollers, the same have their spindles mounted in bearings 147 and 148, which are similar in construction to the bearings 110 but are not provided with clips. These bearings 147 and 148 are secured to extensions of the main frame located respectively on the gearing and feed sides of the press. The form duct roller 53 has its spindle mounted in bearings 149 and 150 upon the outer ends of the pivoted arms 151 and 152, respectively. These arms are keyed or pinned to a transverse shaft 153 which is suitably journaled in bearings 154 and 155 located upon the frame structure at opposite sides of the press. The shaft 153 also has keyed or pinned to it a pair of arms 156 and 157 115 which carry cam rollers 158 and 159 at their outer ends. These cam rollers ride upon the bed 34 as it reciprocates. As they travel along their path upon the bed, the cam roller 158 encounters a depression 161 and the cam 120 roller 159 encounters a depression 160. When these depressions are encountered the duct roller 53 is lowered and because of the locations of these depressions it is lowered 125 into engagement with the ink plate. When 130

the point is reached at which the duct roller 53 is to leave the ink plate, the cam rollers 158 and 159 pass to the normal face of the bed again and thereby raise the duct roller 5 up into engagement with the associated ink distributing roller 56. In this way upon each reciprocation of the bed 34 the duct roller 53 takes up ink from the ink plate and transfers it to the associated roller 56.

10 By varying the length and position of the cam depressions 160 and 161, ink may be taken up by the form duct roller from any desired portion of the ink plate and the balance left for the form inking rollers 54 and 15 56 which also engage the ink plate in its reciprocations.

The form distributing rollers 56, 57, 58, 20 59 and 60 have their spindles mounted in bearings in a movable frame consisting of the side members 162 and 163 which are connected by rods 164 and 165. These side frames are connected to the main frame by links, the links 166 and 167 connecting side member 162, and the links 168 and 169 connecting the side member 163. The distributing roller frame may be moved upon its links so as to raise the distributing rollers up out of engagement with the associated form rollers and the form duct roller, and 25 thereby leave all the rollers readily available for inspection and repair. In order to raise the distributing roller frame, the link 169 has a segment 170 secured so as to rotate with it about its pivot. This segment is 30 provided with worm teeth so as to coöperate with a worm 171 mounted upon a suitably journaled shaft 172 which is actuated from a hand wheel 173 through bevel gear wheels 174 and 175. As the hand wheel 173 is rotated, the link 167 raises the distributing roller frame from the position shown in Fig. 6 to that shown in Fig. 8.

Two of the form distributing rollers, namely, those designated 56 and 60, are positively rotated through the agency of rack 170', pinions 171' and 172' meshing with said rack and driving gear wheels 173' and 174' on the spindles of said rollers, respectively. The rack 170' is mounted upon the 45 bed 34 and moves with it. The pinions 171' and 172' are mounted on spindles projecting from extensions 175' of the main frame. In operation the oscillating movements of the rack 170' are transformed into rotary movements of the rollers 56 and 60.

As the form distributing rollers are raised in response to the operation of the hand wheel 173, the spindles of the rollers 57 and 59 are raised at one end so as to 50 lift the rollers out of engagement with their companion composition rollers 56, 58 and 60. This is brought about by providing a bar 176 to engage the under side of the spindles as the distributing roller frame is 55 being elevated. The bar 176 normally lies

far enough below the spindles to allow the rollers 57 and 59 to properly engage their companion rollers but when the parts are moved into the position of Fig. 8, the bar 176 raises the spindles in the manner explained. This is accomplished by connecting the opposite ends of the bar 176 to crank arms 177 and 178 which are fixed so as to rock with the links 168 and 169 as the distributing roller frame is moved.

The movement of the distributing roller frame to its nonoperative position is also utilized to raise the spindles of the form inking rollers 54 and 55 at one end so as to lift these rollers clear of the form and the inking plate in case the bed should be reciprocated. For this purpose a plate 179 is arranged to slide upon an extension 180 which is fixed to the main frame. Screws 181 extending through a slot in the member 180, serve to guide the plate 179 in its up-and-down movements. The plate 179 has a cam-engaging portion 182 at its lower end which cooperates with a cam 183 which is pivoted to a fixed portion of the frame 25 at 184. The cam 183 is moved by a connecting rod 185, which is in turn connected to a crank arm 186 mounted upon the same spindle as the gear segment 170 and so as to rotate with it. As the segment is rotated, 30 the cam 183 raises and lowers the plate 179 with a corresponding raising and lowering of the spindles of the form inking rollers 54 and 55. Thus we see that by operating the hand wheel 173 the form distributing rollers may be elevated into a suitable position for inspection and repair or replacement of rollers and at the same time the various rollers are moved out of engagement with each other so as to prevent their deformation.

As before pointed out, rollers 47, 50, 56 and 60 are vibrator rollers, and the first two are actuated from the rock-shaft 52, and the latter two from the rock-shaft 61. 45 The spindles of these rollers are provided with collars 187 and 188 for coöperation with extensions 189 from the upper ends of cross arms 190 and 191 located upon the upper ends of the rock-shafts 52 and 61, 50 respectively. As these shafts are rocked, their arms 190 and 191 are likewise rocked to give a reciprocating movement to the vibrator rollers. The shafts 52 and 61 are suitably mounted in brackets on the side 55 of the main frame 30. In Fig. 13 one of these brackets is illustrated at 192, and in Fig. 11 another is illustrated at 193. Shaft 52 is provided with a crank arm 194 which is connected at its outer end by a rod 195 to a crank arm 196 mounted loosely upon the rock-shaft 61. The latter is also provided with a crank arm 197 which is keyed to it and in the form shown lies directly beneath the arm 196. As the arm 196 is 60

moved back and forth its movements are transmitted through the rod 195 and arm 194 to rock-shaft 52. As arm 197 is moved back and forth, its movements are transmitted directly to rock-shaft 61. The arms 196 and 197 are actuated from an oscillating head 198 having two grooved arms 199 and 200 which coöperate with the arms 196 and 197, respectively. This head is mounted upon a vertical spindle or rock-shaft 201 which is journaled in a bracket 202 mounted upon the frame 30. The lower end of the rock-shaft 201 is provided with an arm 203 which has a cam roller 204 extending downward from its outer end into the cam groove of a cam 205 keyed to the transverse shaft 80. As the latter is rotated, the cam 205 moves the arm 203 back and forth so as to rock the shaft 201 and the head 198 with its arms 199 and 200. The connections of the arms 196 and 197 with the arms of the head 198, are adjustable so as to vary the extent of the oscillating movements of the shafts 62 and 51. This adjustment may be made to vary from zero to a maximum in each instance by shifting the connecting bolts 206 and 207. Where these bolts are in line with the rock-shaft 201, no oscillation is produced. As they are moved away from this position oscillation begins and continues to increase according to the extent of the movement. By being able to reduce the oscillation in this way to zero, I am enabled to print with two colors of ink without having the colors overlap or intermingle. As clearly shown in Fig. 12, the bolt 206 passes through a slot in the arm 196 and by means of the washer 208, shoulder 209 and nut 210, may be securely fixed in position upon the arm 196. It is provided at its lower end with an anti-friction roller 211 which engages the walls of the groove in the arm 199 of the head 198. The bolt 207 has the same parts and they are similarly arranged with reference to the arms 197 and 200.

In addition to moving the ink plate rollers out of their operating positions by utilizing the previously described clip construction of Figs. 14 and 15, I also provide for lifting one end of all the ink plate rollers up high enough so as to clear the ink plate in its reciprocations. I accomplish this by raising the plate 112 by means of cam levers 212 and 213 which are pivoted near their upper ends to a fixed portion of the frame and are connected at their lower ends to a longitudinally movable rod 214. The upper end of each of these levers 212 and 213 is provided with a cam face 215, as clearly shown in Fig. 20, which operates against a pin 216 extending laterally from the movable frame 212 into the path of movement of the cam 215. The pins 216 extend through the frame plate 112. Their inner

ends are engaged by the cam faces 215 on the cam levers 212 and 213 and their outer ends ride up and down in guiding slots formed in projections 212' and 213' of the main frame structure. As the rod 214 is moved from the position shown in Figs. 1 and 20, the cams 215 upon the levers 212 and 213 engage their respective pins and raise the frame 112 and thereby raise one end of each of the several ink plate rollers. It will be noted that the gearing by which the rider vibrator rollers 47 and 50 are rotated is at the opposite side of the machine and therefore that the coöperating wheels will not be thrown out of mesh.

In addition to performing this function, I provide a projection 217 upon the cam lever 213 which is adapted to engage the arm 90 to raise the fountain duct roller slightly out of engagement with the fountain roller whenever the ink plate rollers are elevated at one end. It will be seen that as the arm 90 is moved by the projection 217, the fountain duct arms 86 and 87 will also be raised because arm 90 is integral with arm 87, and consequently the fountain duct roller 42 will be raised out of engagement with the fountain roller 43.

In addition to raising these several rollers out of operative position, I provide a cam lever 218 for raising the form duct roller 53 out of ink plate engaging position. As shown more clearly in Fig. 5, the cam lever 218 engages a pin 219 which extends laterally from the arm 152 at a point directly beneath the bearing 150. As this cam lever is oscillated, the outer end of the arm 152 is raised and lowered with a corresponding movement of the form duct roller 53. The cam lever 218 is connected at its lower end like the cam levers 212 and 213 to the reciprocating rod 214, which is offset so as to give a proper degree of movement to the cam lever 218.

The operation of the rod 214 to actuate the cam levers 212, 213 and 218, is brought about by a pedal 220 extending through a footboard 221 located at the feed side of the press. The lower end of the pedal rod 222 is connected to an arm 223 which is mounted upon and secured to a sleeve 224 surrounding a transverse rock-shaft 225. The end of the sleeve 224 adjacent to the gearing side of the machine is connected to a crank arm 226, and the upper end of this arm is connected to the end of rod 214. As the pedal 220 is moved up and down, the rod 214 is moved back and forth to actuate the cam levers to move the parts as just explained. A spring 227 connected at one end to the arm 223 and at the other end to the footboard 221, yieldingly holds the pedal in its normal position. A pin 228 extending transversely of the pedal, cooperates with a cross-shaped slot 229 in the

footboard 221 to hold the pedal in depressed position. This result is accomplished by moving the pin down through the wide portion of the slot and then rocking the pedal about its pivotal connection with arm 223 to bring the pedal into the narrower portion of the slot 229 with the pin 228 beneath the adjacent overhanging portions of the footboard 221.

10 The impression cylinder 39 is driven from the main drive shaft 81 by means of the drive pinion 82 meshing with gear wheel 230 which in turn meshes with gear wheel 231 carried upon the impression cylinder.

15 The impression mechanism of the press includes eccentrics 232 and 233 mounted in the journal boxes 37 and 38 and frame extensions 35 and 36, respectively, both eccentrics being operated from a rock-shaft 234,

20 the former by crank arms 235 and 236 connected by a rod 237, and the latter by crank arms 238 and 239 connected by a rod 240. The requisite oscillations are given to the rock-shaft 234 by means of a pin 241 mounted at the end of an arm 242 upon shaft 234, and a coöperating latch 243 carried at the outer end of an oscillating arm 244, which is actuated by a cam roller 245 working in a cam groove 246 upon the inner face of the

25 gear wheel 79. As the latter rotates, the latch is moved back and forth and the cylinder is given its proper impression movements. An arm 247 is secured to the end of rock-shaft 225 and the latter is provided

30 with an arm 248 which is connected to the lower end of the rod 249 of the pedal 250. By depressing this pedal, the shaft 225 is rocked and the arm 247 is raised. This arm is provided with a groove on its inner face

35 and the upper and lower walls of the groove coöperate with a pin 251 which extends laterally from the latch 243. As the arm 247 is raised it lifts the latch 243 so that the pin 241 will pass out of its normal engaging position in the slot or notch in the latch. As the latch 243 moves to the right, as viewed in Fig. 1, the long point at the forward end of it will still engage the pin 241 and bring it into position to raise the

40 impression cylinder. In other words, it will draw the pin 241 as far as the latch 243 moves toward the right, and thus raise the cylinder to clearance position. Upon the return movement of the latch, however, the

45 pin 241 will not be engaged to cause the impression cylinder to be lowered, but the latch 243 will ride freely over the pin 241 and the cylinder will be left in its elevated position. In this way the impression cylinder is always raised to its clearance position no matter when the impression mechanism may be tripped. As long as the arm 247 holds the latch 243 in its elevated position, the pin 241, after once being moved to

50 55 60 65 its right hand position as viewed in Fig. 1,

will remain there until the arm 247 allows the latch 243 to again fall so as to allow its slot to engage the pin 241. As clearly illustrated, the springs 253 and 254 operate between projections upon the upright portions 35 and 36 of the main frame and projecting shoulders upon the cylinder journal boxes. Their function is to counterbalance the weight of the cylinder and the parts which move with it. This cylinder tripping mechanism allows the impression mechanism to be thrown out of action and thereupon leaves the cylinder elevated so that the bed may be reciprocated without its co-operating action. In this way the form may be inked without producing an operation of the impression cylinder. This impression mechanism is similar to that disclosed in the patent to Miehle No. 550,992, granted December 10, 1895, and in itself forms no part of the present invention. I have, however, provided an interlocking member 255 by which the pressing of the single pedal 250 will not only actuate cam levers 212, 213 and 218, to raise the rollers in the way described, but also trip the impression mechanism so as to leave the cylinder in its elevated position. This interlocking member 255 is provided with a forked lower end 256 which straddles the pedal rod 249 so that no matter to what extent the pedals 220 and 250 are oscillated about their pivotal connections with their arms 223 and 248, the forked end will still engage the rod 249. The upper end of the interlocking member 256 is provided with a lip or shoulder 257 which is adapted to engage the lower edge of the pedal 250, but which may be thrown out of engagement with it by oscillating the pedal 220 into the left-hand portion of the slot, as shown in Fig. 3, while leaving the pedal 250 in the position illustrated in that figure. A set-screw 258 secures the interlocking member 255 to the pedal rod 222. The arm 248 like the arm 223, is provided with a spring 259 to return the pedal 250 to normal position. The pedal 250 is also provided with a transverse pin 260 which cooperates with a T-shaped slot 261 in the footboard 221, in a manner similar to that described in connection with pedal 220. When the shoulder 257 is out of engagement with the pedal 250, then the latter may be operated without actuating pedal 220. On the other hand, even though shoulder 257 is in position to be engaged by pedal 250, yet pedal 220 may be operated without in any way operating pedal 250. When the shoulder 257 is in position to be engaged by pedal 250, which is the position shown in Fig. 1, the act of pressing upon the pedal 250 trips the fountain duct roller 42, the form duct roller 53 and the impression cylinder. When the shoulder 257 is not in position to be engaged by the pedal 250, the

8
act of pressing down the latter has no further function than to trip the cylinder. In this connection it may also be pointed out that when the rod 214 is actuated as a result 5 of pressing down the cylinder trip pedal 250, the roller frame 212 is not raised by the associated cam levers 212 and 213 because the movement of the rod 214 is insufficient for this purpose, although sufficient to actuate 10 the duct rollers 42 and 53, as before stated. If it is desired to raise the roller frame 212, it is necessary to further depress the pedal 220 and to hold it in locked position when thus depressed. Thus the actuation of pedal 15 220 by direct application of the foot gives a greater movement of the rod 214 than is given by depressing the cylinder trip pedal 250 by the foot.

In Fig. 2 I have illustrated in diagram a 20 modified arrangement of form rollers in which there are three form inking rollers 262; a single form duct roller 263, and five ink distributing rollers designated 264 and 265. In this modification the rollers 265 are steel 25 rollers and the others composition rollers. In this diagram the impression cylinder is designated 266. From the previous description it will be readily understood how these various rollers are to be mounted and operated.

It is clear that in carrying out my invention other numbers and arrangements of form inking and other rollers may be employed just as well as the number and arrangement herein disclosed. Likewise, 35 many other alterations and modifications may be made in the arrangements and details of the parts without departing from the spirit and scope of my invention. I 40 therefore do not wish to be limited to the exact disclosure herein presented, but aim to cover all such alterations and modifications by the terms of the appended claims.

What I claim as new and desire to secure 45 by Letters Patent of the United States is:

1. In a printing press, the combination with an impression cylinder and reciprocating bed, of form inking rollers, ink distributing rollers for supplying ink to said form 50 inking rollers, a supporting frame having sockets into which the shafts of said distributing rollers extend in all positions of said frame, a main support, and radius links pivoted to said support and to said frame at 55 normally different distances from the impression cylinder, the connection of each link to said frame being nearer to said cylinder than its connection to said support, whereby said frame and impression rollers 60 may be swung up and away from said inking rollers and away from said cylinder.

2. In a printing press, the combination of an impression cylinder and reciprocating bed, of form inking rollers, ink distributing 65 rollers for supplying ink to said form in-

king rollers, a supporting frame having sockets into which the shafts of said distributing rollers extend in all positions of said frame, a main support, and means acting between said support and frame to swing said frame and distributing rollers up and away from said inking rollers and away from said cylinder. 70

3. A printing press inking mechanism comprising form inking rollers, associated distributing rollers, a reciprocating ink plate, an oscillating form duct roller for transferring ink from said plate to said distributing roller, means for oscillating said form duct roller in response to the reciprocations of said plate, and means for raising said duct roller out of the path of travel of said plate and independently of the position of said plate. 75

4. A printing press inking mechanism comprising form inking rollers, associated distributing rollers, a reciprocating ink plate, an oscillating form duct roller for transferring ink from said plate to said distributing rollers, means for oscillating said form duct roller in response to reciprocations of said plate, a cam pivoted beneath one end of said duct roller and operative to raise said roller above the path of travel of said plate, and an actuating bar secured to said cam and operative to cause said cam to assume its different operative positions. 80

5. A printing press inking mechanism comprising form inking rollers, associated distributing rollers, a reciprocating ink plate, an oscillating form duct roller for transferring ink from said plate to said distributing rollers, means for oscillating said form duct roller in response to reciprocations of said plate, a cam pivoted adjacent to one end of said duct roller and operative to raise said roller above the path of travel of said plate, a bar secured to a portion of said cam, and a pedal connected to said bar and operative through it to cause said cam to assume its different operative positions. 90

6. A printing press inking mechanism comprising form inking rollers, a movable frame, a series of distributing rollers journaled in said frame and operative to supply ink to said form inking rollers, a member engaging portions of certain of said distributing rollers and adapted when elevated to raise said certain rollers out of contact with adjacent distributing rollers, connections between said movable frame and engaging member to raise the latter as said frame is moved and thereby separate said adjacent distributing rollers, and means for moving said frame relative to said form inking 105 rollers. 110

7. A printing press inking mechanism comprising form inking rollers, a movable frame, a series of distributing rollers journaled in said frame and operative to supply 120 ink to said form inking rollers, a member 125

ink to said form inking rollers, a support, radius links pivoted to said support and frame and having extensions upward beyond their connections to said frame, a member pivoted to said extensions and normally engaging the underside of portions of certain of said distributing rollers, and means for shifting said frame and links to move said distributing rollers away from said form inking rollers and to raise certain of said distributing rollers out of contact with others.

8. A printing press inking mechanism comprising form inking rollers, associated distributing rollers, a reciprocating ink plate, an oscillating form duct roller for transferring ink from said plate to said distributing rollers, means for oscillating said form duct roller in response to reciprocations of said plate, ink plate distributing rollers, a frame for supporting said ink plate distributing rollers, a main or supporting frame, a cam pivoted to said main frame adjacent to one end of said form duct roller and operative to raise said roller above the path of travel of said plate, other cams on said main frame for raising said ink plate distributing roller frame, and means for actuating said cams to simultaneously raise said duct rollers and ink plate distributing roller frame, whereby said form duct roller and said ink plate distributing rollers are raised clear of the path of travel of said plate.

9. A printing press mechanism comprising an ink fountain, a fountain roller, a fountain duct roller, supporting arms for said fountain duct roller, an auxiliary arm, a spring acting upon said auxiliary arm to normally hold said duct roller against said fountain roller, an additional arm, a cam lever for engaging said additional arm, means for actuating said cam lever to raise said fountain duct roller out of engagement with said fountain roller, an arm loosely pivoted on the same center as said fountain duct roller supporting arms, and means for periodically actuating said loosely pivoted arm to move said fountain duct roller to and fro.

10. A printing press mechanism comprising a reciprocating ink plate, an ink fountain, a fountain roller, a supporting frame, fountain duct roller arms pivotally mounted on said frame, a fountain duct roller extending between the ends of said arms, an auxiliary arm integral with one of said fountain duct roller arms, a spring-pressed rod co-acting between said auxiliary arm and said frame to normally hold said duct roller against said fountain roller, a second arm integral with one of said fountain duct roller arms, a cam lever for engaging said second arm, means for actuating said cam lever to raise said fountain duct roller out

of engagement with said fountain roller, a third arm integral with one of said fountain duct roller arms, and a coöperating arm loosely pivoted upon the same center as said fountain duct roller arms, and means for periodically actuating said latter arm to move said fountain duct roller through the full extent of its stroke.

11. A printing press inking mechanism comprising a reciprocating ink plate, ink plate distributing rollers, a frame in which said rollers are journaled, a main or supporting frame, an ink fountain adjacent to said distributing rollers, a fountain roller, a fountain duct roller for conveying ink from said fountain roller to one of said distributing rollers, and mechanism on said main frame operative to raise said roller frame and thereby lift said rollers clear of the path of travel of said plate and to raise said fountain duct roller free from engagement with said fountain roller.

12. A printing press inking mechanism comprising a reciprocating ink plate, ink plate distributing rollers, a frame in which said rollers are journaled, a main or supporting frame, cams on said main frame operative to raise one end of said roller frame, an ink fountain adjacent to said distributing rollers, a fountain roller, a fountain duct roller for conveying ink from said fountain roller to one of said distributing rollers, stop mechanism for raising said duct roller free from engagement with said fountain roller, and means for simultaneously actuating said cams and stop mechanism.

13. A printing press inking mechanism comprising form inking rollers, associated form distributing rollers, a reciprocating ink plate, a form duct roller for transferring ink from said plate to said form distributing rollers, an ink fountain, a fountain roller, a fountain duct roller for transferring ink from said fountain roller to said ink plate, means responsive to the to-and-fro movements of said ink plate to oscillate said form duct roller between said ink plate and one of said distributing rollers, means similarly responsive to the to-and-fro movements of said ink plate to oscillate said fountain duct roller between said fountain roller and said ink plate, and means operative when the mechanism is at rest for raising said form duct roller out of the path of travel of said plate and said fountain duct roller out of engagement with said fountain roller.

14. A printing press inking mechanism comprising form inking rollers, associated form distributing rollers, a reciprocating ink plate, a form duct roller for transferring ink from said plate to said form distributing rollers, means responsive to the to-and-fro movements of said ink plate to

- oscillate said form duct roller between said plate and one of said distributing rollers, a cam for raising said form duct roller out of the path of travel of said plate when the 5 mechanism is at rest, an ink fountain, a fountain roller, a fountain duct roller for conveying ink from said fountain roller to said ink plate, means responsive to the to-and-fro movements of said ink plate to oscillate said fountain duct roller between said fountain roller and ink plate, stop mechanism operative when the reciprocating ink plate is at rest for raising said fountain duct roller out of engagement with said 10 15 fountain roller, and an actuating bar for actuating said cam and said stop mechanism.
15. A printing press inking mechanism comprising a main or supporting frame, a series of ink distributing rollers, means for 20 rotating said rollers, a vibrator arm secured to certain of said rollers and operative to move them back and forth longitudinally upon their companion rollers as they rotate, a rock-shaft carrying said vibrator arm, an 25 arm secured to said shaft, a second rock-shaft, an arm on said second rock-shaft, a connection between said rock-shaft arms adjustable lengthwise of said arms to vary the degree of rotation and hence the degree of 30 to-and-fro movement of the movable ink distributing rollers, and means for rocking said second rock-shaft.
16. A printing press inking mechanism comprising a main or supporting frame, 35 form inking rollers, a reciprocating ink plate, means for supplying ink to said plate, a set of ink plate distributing rollers, a set of form distributing rollers, certain rollers of each of said sets being movable to and fro 40 longitudinally upon their companion rollers, means for transferring ink from said ink plate to said form distributing rollers, oscillating arms secured respectively to the movable rollers of said sets, a rock-shaft for 45 supporting and rocking each of said oscillating arms, a rotary driving member, and connections between said member and said rock-shafts whereby the latter are simultaneously rocked and the movable rollers of 50 each of said sets moved to and fro as said member rotates.
17. A printing press inking mechanism comprising a main or supporting frame, form inking rollers, a reciprocating ink 55 plate, means for supplying ink to said plate, a set of ink plate distributing rollers, a set of form distributing rollers, certain rollers of each of said sets being movable to and fro longitudinally upon their companion rollers, 60 means for transferring ink from said ink plate to said form distributing rollers, oscillating arms secured respectively to the movable rollers of said sets, a rock-shaft for supporting and rocking each of said oscillating arms, a rotary driving member, a

driving rock-shaft actuated by said rotary driving member, arms on said driving rock-shaft, arms on said oscillating arm rock-shafts, and a connection from each of said latter arms to each of said former arms, 70 whereby the rotation of said driving member rocks said rock-shafts and oscillating arms and thereby reciprocates the movable rollers of each of said sets of distributing rollers.

18. A printing press comprising an impression cylinder, a form carrier, form inking rollers, distributing rollers for supplying ink to said form inking rollers, a reciprocating ink plate, a duct roller for transferring ink from said plate to said distributing rollers, means for normally holding said cylinder out of form engaging position, mechanism for periodically bringing said cylinder into form engaging position, pedal operated mechanism for rendering said last 85 mentioned mechanism ineffective while the press is running, means for elevating said duct roller above the path of travel of said plate, pedal operated mechanism for operating said elevating means, and interlocking 90 connections between said pedal operated mechanisms whereby the operation of one will operate the other but the operation of the other will not operate the one.

19. A printing press comprising an impression cylinder, a form carrier, form inking rollers, a reciprocating ink plate, means for conveying ink from said plate to said form inking rollers, ink plate distributing rollers, a fountain, a fountain duct roller 100 for conveying ink from said fountain to said ink plate distributing rollers, means for normally holding said cylinder out of form engaging position, mechanism for periodically bringing said cylinder into form engaging position, pedal operated mechanism for rendering said last mentioned mechanism ineffective while the press is running, means for elevating said fountain duct roller to render it inoperative to carry ink, pedal 105 operated mechanism for operating said elevating means, and interlocking connections between said pedal operated connections whereby the operation of one will operate the other but the operation of the other will 110 not operate the one.

20. A printing press inking mechanism comprising ink distributing rollers, a frame for said rollers, bearings mounted on said frame and having slot-like depressions for 120 receiving the spindle-bearing ends of said rollers, a hook adapted to close over the spindle positioned in said depression, an opening in said bearing directly beneath said depression, a hub on said hook or clip 125 extending into said opening, a pivot for said hook or clip extending through said hub and said opening into engagement with said bearing, a coiled spring surrounding said pivot and secured at one end to said hub and 130

at the other end to said bearing and serving to hold said hook or clip yieldingly in closed position, and a seat formed on the upper side of said hook for receiving the spindle 5 when lifted out of said depression and placed thereon to separate said roller from adjacent rollers.

21. A printing press inking mechanism comprising ink distributing rollers, a frame 10 for said rollers, bearings mounted on said frame and having slot-like depressions for receiving the spindle bearing ends of said rollers, a hook or clip pivoted to one of said bearings directly beneath said depression 15 and adapted to close over the spindle positioned in said depression, a seat formed on the upper side of said hook for receiving the spindle when lifted out of said depression and placed thereon to separate said 20 roller from adjacent rollers, and an oil pocket formed in the body of said bearing at one side of said depression communicating with the bearing at the bottom of said depression.

25. 22. A printing press inking mechanism comprising a main or supporting frame, two sets of ink distributing rollers, means for rotating said rollers, a vibrator arm for each set of rollers extending transversely of 30 said rollers adjacent to their ends and operatively engaged at its ends with the ends of certain of said rollers and movable with a slight oscillatory movement to move said operatively engaged rollers back and forth longitudinally upon their companion rollers, a vibrator shaft secured to an intermediate point of each of said vibrator arms, a driving member, driving connections between said driving member and each said vibrator 35 shaft, and means for adjusting said connections to vary the degree of to-and-fro movement of the said rollers of each set independently of each other.

23. A printing press inking mechanism 40 comprising a main or supporting frame, two sets of ink distributing rollers, means for rotating said rollers, a vibrator arm for each of said sets secured to certain of the rollers of each of said sets respectively and operative to move them back and forth longitudinally upon their companion rollers as they 45 rotate, a rock-shaft for each of said vibrator arms, an arm secured to each of said rock-shafts, an additional rock-shaft, arms on

said additional rock-shaft, means for rock- 55 ing said additional rock-shaft, connections between the arms on said additional rock-shaft and the arms on said first mentioned rock-shafts to actuate the latter from the former, and means for adjusting the point 60 of connection of said connections to said additional rock-shaft arms relative to the axis of said additional rock-shaft.

24. A printing press inking mechanism comprising a main or supporting frame, two sets of ink distributing rollers having certain of their rollers movable back and forth longitudinally on their companions, a vertical vibrator shaft for each set of rollers, a vibrator arm secured at an intermediate point to each of said shafts and extending transversely of said rollers adjacent to their ends and operatively engaging the ends of the longitudinally movable rollers, a common driving rock-shaft and connections between said common driving rock-shaft and each of said vibrator shafts for communicating a rocking motion to them, and means for varying the connections between said common driving shaft and each of said vibrator shafts in order to vary the longitudinal movements of said movable rollers of 75 said sets individually from zero to a desired maximum.

25. A printing press inking mechanism 80 comprising a main or supporting frame, a reciprocating bed, an ink plate, a set of form ink distributing rollers, a set of plate ink distributing rollers, each of said sets including vibratory rollers movable back and forth 85 longitudinally upon their companions, a vibratory shaft for each set of rollers, a vibrator arm for each set of rollers connected to said shaft at an intermediate point and having its ends operatively engaging the longitudinally movable rollers of the associated set, a common driving rock-shaft and individual connections between said rock-shaft and each of said vibrator shafts, and means for giving each of said connections independent adjustments so as to vary the action 90 of the vibrator rollers of each set independently from no vibratory movement to a considerable vibratory movement.

In testimony whereof I have hereunto subscribed my name this 5 day of January, A. D. 1916.

CYRUS A. McCAIN.
